UNITED STATES PATENT OFFICE.

KEITH K. KELLER, OF MINNEAPOLIS, MINNESOTA.

METHOD OF MARKING CAPSULES.

Application filed December 11, 1926. Serial No. 154,158.

The present invention has to do with a capsule of the usual gelatine type or modifications thereof, or other means for dispensing medicine in a soluble container, and relates particularly to means for marking such capsule or container whereby it may be made to carry indicia as selected by the maker or user.

Included among the objects of the invention to be hereinafter described, are the following:

An unique capsule or container having as a part thereof externally visual data indicating its origin, as for example, the name of the physician whose prescription is therein contained, or the name of the druggist who compounded the prescription, or the name of the manufacturer of the capsule or of the medicine therein; an unique means for marking a capsule with figures, words, letters, or insignia; a novel method for impressing upon a capsule identifying data, such as the name of a physician or druggist, or manufacturer, whereby such insignia is visually impressed upon such capsule without affecting the solubility thereof or modifying the medicinal effects to be obtained by the contents; an unique method of marking a capsule or the like whereby the name of a physician, druggist, or manufacturer, or a trademark may be impressed thereupon or associated therewith and the purchaser of such capsules thereby will know its origin. These, and such other objects as may hereinafter appear, are obtained by a novel process for marking a capsule, by the novel arrangement of the elements herein to be disclosed, and by the combination of marking elements particularly adapted for the especial purpose hereinafter set forth.

For a better understanding of the invention, reference should be had to the single sheet of drawing hereby made a part of this description, and in which:

Figure 1 is a perspective view of a capsule using one form of the invention herein described;

Figure 2 is a perspective of the die used for marking a capsule such as is shown in Figure 1.

Like reference characters are used to designate similar parts in the drawing and in the description which follows.

Only one form of the invention is disclosed. Numerous other forms could be described, but for the purpose of describing the

nature of the invention, the form illustrated has been deemed all that is necessary.

Generally in the structure of a conventional gelatine capsule for apothecaries' use, there are two parts, both transparent. The capsule here described comprises a body having a closed end and a cap, the cap being closed at one end and being adapted to telescope upon and around the body. The body is filled with powdered, semi-solid, or liquid material in the usual way, and the cap is slipped thereover as has been the practice for many years.

Preferably the marks employed and as disclosed in Figures 1 and 2 are placed upon the body A of a capsule. The cap B thereof is transparent, and such marking will ordinarily show therethrough. The capsule may be colorless, the usual form, or it may be tinted with pink as is frequently found, or with red as is also used, or with any other color.

Of course a transparent capsule is to be preferred, but if the capsule employed is not transparent, the marking may be disposed upon the body thereof so that it is not covered when the cap is slipped thereover.

When a transparent capsule is used, the marking may extend the full length of the truly cylindrical portion of the body.

Perhaps the simplest way of impressing upon the body of the capsule indicia such as is herein described is to provide a holder for the body and which is adapted to be seated therein during the marking process. This holder is not altogether necessary for the pressure upon the capsule during the marking process is not enough to crush it if the marking die is skillfully handled.

In Figure 2, is shown a marking die C made of hard steel such as tool steel. The die material usually is heated to a temperature at which it liquefies when all the carbon possible is extracted. About ninety-two one hundredths (92/100%) per cent of carbon is next added, as the process of making the die is completed. This material has been selected after a large number of experiments because of its peculiar qualities which are conducive to good results in marking gelatine capsules, and because when used with wax, or with a combination of wax and gelatine, it produces superior results.

The die C has the letters D to be impressed upon the capsule A in relief. Said

die C is heated to a temperature approximating that of boiling water, or higher, and then it is brought into contact with a molten mass of colored liquid wax, or colored wax and gelatine, the proportions thereof being from one half wax to two thirds wax. Sealing wax may be used without the gelatine but in combination with gelatine, it appears to adhere more strongly than when used without this addition. Upon a colored capsule, a white wax is employed.

The next step in the process after dipping the die in the wax is to bring the die completely covered over at its lettered end with a thin layer of the wax-gelatine composition into contact with the capsule suitably filled, (although filling is not necessary), or a capsule held upon a spindle or holder as above described. In most instances, the capsule to be marked may be held in the hand.

The die C carries a small portion of wax or wax compound upon the projecting material D thereof and a larger quantity in the space between the raised letters. It is held against the body A of the capsule for a short time, varying from one-fifth ($\frac{1}{5}$) to two (2) seconds. A short period of contact is to be preferred when the die C is heated to a higher degree of temperature.

The pressure employed is sufficient to hold the die C securely against the capsule but without any destructive deformation of the capsule material. The heat of the die C and the wax carried thereby causes a slight indentation or depression upon the body of the capsule following the lines of letters D and in the indentation thus formed and which is relatively shallow, the wax carried by the letters D of the die C is deposited.

With the removal of the die C, the excess portion of wax, that is, that portion thereof intermediate the letters D of the die C, is removed with the die C, leaving upon the capsule A an inwardly pressed portion showing the mark upon the die C and filled with wax of the color selected. The capsule A is then ready for use and may be filled if it is then required, or a number thereof may be prepared in advance and kept on hand for future use.

It is contemplated that a die C as herein described may be attached to an apparatus for forming the body of capsules, and with the formation of capsules, an impression of the die C covered with wax may be obtained. Thus a gelatine capsule may be marked during the process of its manufacture, one additional step in its manufacture being made necessary.

Usually a color of wax contrasting with the capsule is employed as for example red wax (and gelatine) upon a colorless capsule or a white wax mixture upon a tinted capsule. The letters thus formed will be clearly visible to the eye. The different sizes of capsules may be treated with different die to obtain larger letters or one die may be used for all sizes.

A straight edged die rather than one with a curved end is preferred, and the impression of the die C upon the capsule A is preferably obtained by a rotary or arcuate movement of the non-contacting end of the mold so that the impression of the die upon the capsule is of short duration but at the same time complete.

Wax and gelatine such as are impressed upon the capsule are medicinally inert. They make a harmless mixture. It produces no appreciable taste.

By the method herein described, a capsule may be marked with the producer's name, a druggist's name, a manufacturer's name, a trademark, the name of a medicine, or otherwise. In the hands of the patient, the name of the physician, druggist, or manufacturer is noted every time a medicinal dose is taken. This proves an ethical way of advertising for a physician or for a druggist or for a drug manufacturer. It keeps the mark used upon the capsule ever before the patient and also before all of those who come in contact with the patient and the treatment that he is receiving.

For marking capsulated medicines with the name of the content it has a high utility.

An unique and highly useful advertising medium is also produced, without medicinal effect upon the patient and without adding a burden either to the druggist or dispensing manufacturer employing the means herein described.

What I claim is new and desire to procure by Letters Patent of the United States is:

1. The method of marking a capsule with a visible insignia which includes the step of impressing upon the body of such capsule a heated die carrying a portion of wax like material, the impression of such die upon such capsule being insufficient to fracture or deform the capsule and the heat of such die being sufficient to cause a shallow depression in the material of such capsule.

2. A method of marking a capsule with visible indicia which consists in creating an impression in said capsule and simultaneously applying therein a normally solid visible material in its liquid state.

KEITH K. KELLER.
